MAGAZINE PLUG FOR REPEATING
SHOTGUNS

Norman A. Hemmerling, Niagara Falls, N. Y.

Application December 7, 1948, Serial No. 63,904

4 Claims. (Cl. 42—49)

1

This invention relates to magazine plugs for repeating shotguns.

Repeating shotguns usually have a capacity of six or more shells. In connection with the hunting of certain types of game, the laws require that the gun be plugged in such a manner that the gun can only be loaded with a smaller number of shells. The plugs used must be of a nature which cannot be quickly inserted since otherwise a person violating the law could readily insert a plug when he sees a game inspector approaching. On the other hand, it is also desirable that the gun be plugged in such a manner that the user of the same will not have too much difficulty in removing the plug, so that when hunting for other types of game on which no restriction as to number of shells which may be placed into the gun are required, he can fill the magazine of the gun to its capacity.

Heretofore it has been necessary, in order to insert a rod in a magazine to limit the number of shells that can be inserted into the magazine, or to remove such rod, to dismantle the magazine and then again to assemble the same and mount it on a gun. Many owners of shotguns were unable to do this and, consequently, had to take their guns to a mechanic capable of dismantling and reassembling the magazine, whenever it was necessary to place a rod into the magazine or to remove the rod.

One of the objects of this invention is to provide a shotgun plug of efficient and reliable construction which will make it possible for the owner of a gun to readily plug his gun to limit the capacity of the magazine without requiring the services of an expert to insert or remove a plug rod in and from the magazine.

A further object is to provide a gun magazine plug usable with guns of different types and which is efficient, and requires the minimum of alteration of the gun itself.

Other objects and advantages of this invention will be apparent from the following description and claims.

In the accompanying drawings:

Fig. 1 is a fragmentary elevation of a shotgun to which a magazine plug embodying this invention may be applied.

Fig. 2 is an elevation of a part of the gun as indicated by line 2—2, Fig. 1.

Fig. 3 is a view showing a rod or filler which may be inserted into the magazine of the gun to limit the capacity of the same.

Fig. 4 is a longitudinal view, partly in section,

2

on line 4—4, Fig. 2, showing a part of the magazine of the gun.

Fig. 5 is a similar view showing the magazine when plugged to limit the capacity of the magazine.

My invention is illustrated in the accompanying drawings as applied to a well known type of repeating shotgun, but it will be understood that it is not intended to limit the use of this invention to shotguns of this type, since it will be obvious that this invention may be employed in connection with guns of other types having a tubular magazine into which a series of shells are inserted end for end.

15 In the particular gun illustrated in Figs. 1 and 2, 8 represents the barrel of the gun and 9 the magazine tube, which is usually mounted immediately below the barrel and into which shells may be inserted. 10 represents in general the receiver of the gun to which the butt stock (not shown) of the gun is secured and to which the gun barrel may be attached by means of the usual barrel lock screw 11 formed to cooperate with similar internal threads in the receiver, and 12 represents the slide handle which, through the medium of the action slide bar 14 and suitable mechanism contained in the receiver 10, effects the transfer of a shell from the magazine 9 into the gun barrel 8.

20 15 represents a receiver extension by means of which one end of the magazine tube is secured to the barrel 8, and 16 represents a spiral magazine spring contained within the magazine tube, see Figs. 4 and 5, one end of which acts on a follower 17 slidably in the magazine tube. When the gun barrel and magazine tube are attached to the receiver 10, shells may be inserted into the magazine tube by pressing the same against the magazine follower, thus compressing the spring 16.

25 20 When the gun is used, the spring 16 pressing against the follower 17 urges the shells, one at a time, from the magazine into the receiver 10, from which they are positioned in the gun barrel by means of mechanism (not shown).

30 25 The parts thus far described, with the exception of the follower 17 shown, are common in guns now in use and of themselves do not constitute a part of this invention.

In order to apply a magazine plug to the gun for the purpose of limiting the number of shells which can be inserted into the magazine, I provide in the base 29 of the follower, which is generally of cylindrical form and provided with a sliding fit within the magazine tube, an aperture 24, preferably located axially with reference to the

base 20 of the follower. This aperture is so formed that it may be closed by means of any suitable or desired closure. In some types of guns, the base of the follower is made of thin metal so that it may be impractical to use the same with my improvements, and in such cases, a follower having a base of different shape may be substituted for the follower originally supplied with the gun. In the preferred form of my invention illustrated in the drawings, I provide the aperture 21 with screw threads formed to cooperate with a screw 22 which has a threaded engagement in the aperture 21 in such a manner that it can be removed or placed into the aperture as desired. The screw may be provided with the usual screwdriver slot 24 to facilitate turning of the screw. Any suitable means may be provided for holding the follower against turning when the screw 22 is being turned, such for example as one or more holes 26 in the base of the follower, into which an implement may be inserted to hold the follower against turning. When the gun is used in the ordinary manner, without restricting the number of shells which may be placed in the magazine, the screw in the threaded aperture in no way interferes with the normal use and operation of the gun. However, if it is desired to plug the magazine to limit the number of shells which may be inserted into the same, I provide a rod or filler member 25, Figs. 3 and 5, which may be made of metal, wood or other suitable material. This rod or filler 25 is of such diameter that it may be readily passed through the aperture 21 and through the interior of the spiral spring 16. The rod should be of a length substantially equal to the number of shells which are to be excluded from entering the magazine tube. For example, if the gun has a capacity for six shells, one of which will be located in the barrel itself, and five of which are inserted into the magazine tube, and if the law for a certain type of game requires that only three shells may be used in the gun at one time, one in the barrel and two in the magazine tube, then the rod or filler should be of such length as to exclude three shells from the magazine tube. Consequently, when the rod is inserted through the aperture 21 and arranged within the coils of the spiral spring 16, as shown in Fig. 5, the follower 17 will be stopped by the rod from moving to the right in the magazine tube after two shells 27 have been inserted into the magazine tube. It will, of course, be obvious that this rod or filler 25 may be made of any desired length so as to permit the insertion into the magazine tube only of the number of shells permitted by law for hunting certain types of game.

In order to facilitate the removal of the rod from the magazine, if the gun is to be used for hunting game on which no limit to the number of shells in the gun exists, the inner face of the base 20 of the magazine follower is preferably provided with a substantially frusto-conical surface 29 which extends from the aperture 21 to the cylindrical side of the follower. Consequently, if the screw 22 is removed and the gun is held in upright position with the muzzle upwardly, the frusto-conical surface 29 will guide the adjacent end of the rod 25 to the aperture 21 and the rod will readily pass through the aperture so that it can be removed from the gun, whereupon the screw 22 may be replaced in the aperture.

If desired, one end of the rod may be attached to the inner end of the screw 22. The outer edge of the frusto-conical surface 29 forms a seat for

the end of the spring 16, so that the last coil of the spring, which is generally bent in such a manner as to extend perpendicularly to the length of the spring, will exert a uniform pressure against the follower to prevent any tendency of the same to bind in the magazine tube.

In the use of the magazine plug embodying this invention, it will be obvious that if it becomes necessary to plug the magazine so that the gun will be used for hunting certain types of game, the barrel 8 and magazine tube are first disconnected from the receiver 10 in such a manner that the end of the adjacent end of the magazine tube will be readily accessible for applying a screwdriver, coin or other implement to the slot 24 of the screw for removing the same from the base of the magazine follower, an implement being inserted into the hole or holes 26 if necessary to hold the follower against turning. The rod or filler 25 may then be inserted through the aperture 21 to lie within the coils of the magazine spring 16, whereupon the screw 22 is replaced in the threaded aperture. The rod 25, consequently, forms a stop to limit the extent to which the follower may be moved toward the muzzle end of the magazine tube. This muzzle end is closed by a suitable closure member (not shown), which confines the spring 16 within the magazine tube. After the legal number of shells have been inserted into the magazine, further movement of the follower 17 will be prevented, since one end of the rod 25 will engage the closure at the muzzle or outer end of the magazine, while the other end of the rod or filler will engage the follower or screw 22 and thus stop further movement of the follower to the right in Figs. 4 and 5.

When the gun is to be used on game in which no limit exists as to the number of shells which may be contained in the magazine, the screw 22 can be removed and the rod 25 withdrawn from the magazine through the aperture 21, whereupon the screw 22 may be replaced. The operation of inserting the rod or filler or removing the same from the gun is, consequently, easily performed by any user of the gun. However, the insertion of the rod or filler requires the barrel and magazine to be disconnected from the receiver 10, and the operation of removing the screw 22 and positioning of the rod 25 within the magazine requires sufficient time, so that any person using the gun illegally and then attempting to quickly place a rod into the magazine upon seeing a game warden or inspector, will not be able to do so quickly enough to avoid detection.

The magazine plug shown and described has the advantage that the rod which limits the capacity of the magazine may be inserted into the magazine and removed therefrom by merely removing and replacing the screw 22, so that no dismantling and reassembling of the magazine is required to insert or remove the rod.

It will be understood that various changes in the details, materials, and arrangements of parts which have been herein described and illustrated in order to explain the nature of the invention, may be made by those skilled in the art within the principle and scope of the invention, as expressed in the appended claims.

I claim as my invention:

1. In a plug device for a magazine of a repeating shotgun, comprising a follower slidable in the magazine and a helical spring in the magazine acting on said follower to urge the same toward the shell discharge end of the magazine,

that improvement which comprises a threaded aperture in the base of said follower, and a screw removably engaging in said threaded aperture, and a rod of a diameter to permit inserting said rod through said threaded aperture and into said helical spring, said rod when placed in said magazine and after said screw is replaced in said threaded aperture serving to limit the extent to which said follower may move to permit insertion of shells into said magazine.

2. A device according to claim 1, characterized in that the base of said follower has a substantially frusto-conical inner surface extending from said threaded aperture to the inner face of the side wall of the follower to form a seat for one end of said helical spring and to guide said rod to said aperture when it is desired to remove said rod from said magazine.

3. In a tubular magazine for a gun provided with a substantially cylindrical follower having a base and slidable lengthwise in said magazine and spring means in said magazine for urging said follower toward the shell receiving and discharging end of the magazine, that improvement which includes an aperture in the base of said follower, a removable closure for said aperture, and a rod of a diameter less than that of

said aperture and which may be inserted into said magazine through said aperture and retained therein by said closure and which limits the extent to which said follower may move in 5 said magazine to limit the number of shells that may be inserted into said magazine.

4. A device according to claim 3, in which said spring means is a helical spring arranged lengthwise in said magazine and bearing at one 10 end on said follower and within which said rod may be arranged when inserted into said magazine through said aperture, and in which the base of said follower has a substantially frusto-conical inner face extending from said aperture to the side wall of said follower to guide said rod to said aperture when removing said rod from 15 said magazine.
